MONOGRAM STRUCTURE.

Application filed June 8, 1927. Serial No. 197,480.

This invention relates to monograms and has for an object to provide an improved construction wherein removable configurations are provided for the base in order that 5 different configurations for the same base may be used when desired.

Another object of the invention is to provide a monogram wherein a base of a certain design is presented and wherein different letters may be mounted thereon so as to appear 10 as an integral part of the base.

In the accompanying drawing—

Figure 1 is a front view of a monogram disclosing an embodiment of the invention. 15 Figure 2 is a sectional view through Figure 1 on line 2—2.

Figure 3 is a view similar to Figure 1 but showing the base without the letters.

Referring to the accompanying drawing 20 by numerals, 1 indicates a base which is preferably of metal and which is provided with any desired kind of configuration 2, which in the present instance, includes a diagonally positioned panel 3. The base 1, as shown in 25 Figure 2, is provided with a recess 11 in the back which is roughened, whereby adhesive 11' may more readily adhere thereto. Also, from Figure 1 it will be observed that 30 the edges of the base 1 taper so that it will be very difficult for a knife or any other instrument to be placed under the base in an attempt to separate the same from the support. Arranged in the panel 3 are recesses 35 4, 5 and 6. Each of these recesses is provided with a raised portion or fence 7 which is more or less ornamental and conforming to the general ornamentation 2. In the bottom of each recess is arranged a number of indentations 40 8 and also preferably extending through base 1, is an aperture 9 for each recess whereby an instrument may be forced through these apertures from the rear for forcing off any of the letters when not desired.

As indicated in Figure 1, there is provided 45 a letter 10 for each of the recesses 4, 5 and 6, the respective letters 10 being different and may be arranged to represent the initials of a person. These letters are formed of a shape to fit snugly within the rim of frame 7. When 50 it is desired to place a set of letters in the recesses 4, 5 and 6, suitable adhesive is applied to the bottom of the recesses and preferably applied also to the back of the letters 10. The letters are then forced into place as indicated 55 in Figure 1 and said letters snugly fit in the

recesses and thereby give the appearance of being formed integral therewith.

In case it should be desired at any time to remove the letters, such action may be done by applying a solvent for the adhesive, said solvent being applied through the holes 9, and after the adhesive has become soft, an instrument passed through the apertures 9 will quickly remove the letters so that a new set may be applied if desired. 65

It will be noted that when the plate is applied to a supporting surface, such, for instance, as the flat metal surface of an automobile door, there is a margin completely encircling the recess 11 in the back of the plate, 70 which margin firmly contacts with the supporting surface, and has a tight sealing fit thereagainst, so that it is difficult to insert a knife or other instrument to bodily dislodge the monogram from its support. By virtue 75 of this marginal contact the recess 11 provides a secure attachment, even if the adhesive material under the plate should contract.

It will also be noted that at the front face of the plate there is provided a marginal 80 raised border which cooperates with the fences 7 to define a sunken field. When the removable character-bearing elements 5 are emplaced they cooperate with their framing fences to effectively simulate unitary bordered monograms standing out in relief on a sunken ornamental field. 85

The device is adapted for automobiles, clubs, organizations and for other purposes, including handles and pull members for 90 ladies handbags. For instance, if a club adopts a certain monogram, as for instance, the monogram shown by base 1 and ornamental face 2, three recesses may be formed as shown in Figure 3 and then a large number 95 of letters supplied with enough monograms for each member of the club. Each individual member of the club will then select the letters indicating his initials and these can be supplied to his particular base 1 so 100 that when he wears the monogram on his clothes or uses the same in any way, the appearance will be as if the monogram had been specially constructed with his initials. This is true for all of the members. In case one 105 or only two initials are desired, the unused recess may be filled with a plate similar to the plate carrying the letters, and the blank plate may be if desired, provided with an ornamental configuration. 110

As indicated on the drawing, each of the letters 10 is formed by a plate of metal or other substance with enamel or other covering matter on the face, arranged to form the desired letter. It is, of course, evident that instead of having enamel letters, all metal letters could be provided and the letter formation could be made by either a raised or depressed portion in the plate. When mounting the base on an automobile or other support, the hole or recess 11 of the back is filled with cement or other adhesive, and this cement is forced through the various apertures 9 so as to adhere to the back of the letters 10 or to the adhesive mounted on these letters, whereby these letters will be additionally held in place by a lock or rivet formed of adhesive.

What we claim is:

- 20 1. A monogram structure or the like, including a relatively thin base plate, the margin of the rear face of which is adapted to lie flat against a supporting surface, said rear face being formed with a shallow adhesive-receiving recess occupying substantially the entire area of the plate within the support-contacting margin, the front face of the plate having a shallow recess therein, and a flat character bearing unit of no greater thickness than the depth of said last mentioned recess, fitting and adhesively mounted therein, and protected laterally by the walls thereof.
- 25 2. A monogram structure or the like including a relatively thin base plate having

a shallow recess in its rear face adapted to receive adhesive material, the front face of the plate including a raised marginal border to define a sunken field, frame-forming ribs rising from the field and defining shallow pockets, the bottoms of which are substantially flush with the field, and flat character-bearing plates of no greater thickness than the depth of the pockets snugly fitting and adhesively secured therein whereby said plates and frames simulate unitary bordered monograms standing out in relief on the field.

3. A monogram structure or the like including a relatively thin base plate, the margin of the rear face of which is adapted to lie flat against a supporting surface, said rear face being formed with a central shallow adhesive receiving recess, the front face of the plate having a shallow recess therein, a flat character-bearing unit of no greater thickness than the depth of said last-mentioned recess, fitting and adhesively mounted therein, and protected laterally by the walls thereof, said plate having an opening therethrough connecting the recesses whereby adhesive may be extruded rearwardly through said opening as the character-bearing unit is forced home, and exuding into the rear recess defining when dry a locking rivet of adhesive material to retain the character-bearing element in place.
